UNITED STATES PATENT OFFICE.

HENRY GUTTERIDGE AND JOHN HENRY McCONNELL, OF HAMIOTA,
CANADA.

MACHINE FOR FORMING BUILDING-BLOCKS.

SPECIFICATION forming part of Letters Patent No. 784,154, dated March 7, 1905.

Application filed May 27, 1904. Serial No. 210,013.

To all whom it may concern:

Be it known that we, HENRY GUTTERIDGE and JOHN HENRY McCONNELL, subjects of the King of Great Britain, residing at Hamiota, county of Shoal Lake, in the Province of Manitoba, Canada, have invented certain new and useful Improvements in Machines for Forming Building-Blocks; and we do hereby declare that the following is a full, clear, and exact description of the invention, such as will enable others skilled in the art to which it appertains to make and use the same.

This invention relates to new and useful improvements in apparatus designed especially for molding and pressing building-blocks, and is particularly applicable to the manufacture of that class of fire-proof blocks having centrally-arranged apertures therein, which blocks are formed from concrete and similar material.

The object of the invention is to produce a device of the character described which will be comparatively simple in construction and easy of operation and which will so combine the coöperative parts as to produce a structure which may be operated with a minimum expenditure of power, all as hereinafter more fully described, and specifically pointed out in the claims.

In the annexed drawings similar characters of reference indicate corresponding parts in all the views, in which—

Figure 1 is a side elevational view of our improved apparatus. Fig. 2 is a plan view thereof. Fig. 3 is a side elevational view looking in the direction of the arrow P of Fig. 2. Fig. 4 is a longitudinal vertical section taken approximately centrally of Fig. 2. Fig. 5 is a view, partly in section, on line 5 5 of Fig. 3. Fig. 6 is a view, partly in section and partly in elevation, on the line 6 6 of Fig. 3; and Fig. 7 is a vertical sectional view taken approximately on the line 7 7 of Fig. 3. Fig. 8 is an inverted plan view of the plunger-head used with the matrices illustrated herewith.

Referring to the drawings, it will be noted that the structure is supported upon a bed-frame having the base-plate 1 and vertical

plates 2 2 resting thereon, which plates support track-rails 3, upon which track-rails are supported a slidtable table comprising the runners 4 and supporting-plate 5, upon which plate is adapted to be carried a matrix or matrices (represented generally by the reference-letters A B.) Connected with the table-plate 5 are core-supporting plates 7, which plates carry one or more vertically-projecting cores 8, which cores are adapted to form the central orifices in the finished building-block, within the interior thereof, and the end semi-cores 9, which are adapted to form recesses in the ends of the finished building-block, which recesses when placed in juxtaposition to corresponding recesses in the next adjacent blocks will form openings corresponding to the larger openings within a single block. This core-plate is supported in position by means of screw-threaded staffs 10, which project through the table-plate 5 and engage with the core-plate, the nuts 11 being used to secure such staffs to the core-plates, while screw-threaded seats 12 are connected with the table-plate, through which such screw-threaded staffs are projected, so that when the wheels 13 of the staffs 10 are rotatated it will be evident that the core-plates 7 with the cores 8 and 9 thereon are raised or lowered according to the direction of rotation of such end wheels. As will be noted in the drawings, a plurality of core-plates 7 are carried by the table-plate 5, one being arranged approximately at each end thereof, so as to permit the filling of the matrix placed about one set of cores while the contents of the other matrix are being pressed by the press hereinafter described. For the purpose of forming the matrix side plates 14 are provided, which rest upon the table-plate 5, the side plates 14 being of such proportions with relation to the table-plate as to leave a shoulder or seat 15 therebetween comprising a part of the table-plate, upon which may rest a perforated bottom plate 16, forming the portion of the matrix upon which the concrete or other material to be pressed may be placed. End plates 16 are interposed between the side plates 14, and an auxiliary frame 17 is placed upon the

upper edges of the side plates and end plates, so as to provide a temporary auxiliary matrix-frame for the support of the surplus material which will be subsequently pressed into the matrix proper. When the matrix-frame is assembled, the yokes 18, which are pivotally connected to the table-plate 5, as shown in Figs. 3 and 5, are locked in position, so as to hold the several parts of the matrix firmly united, such yokes being pivoted upon the set-screws 19, which are adapted to project into the table-plate, as shown in Fig. 7, whereby a locking-clamp is provided which secures the matrix, including its bottom plate 16, properly in position upon the table-plate 5. A description of one matrix and its appurtenant parts will answer for both, as they are to all intents and purposes constructed in the same manner. The table thus provided is slidable upon the rails 3, and for the purpose of projecting the table longitudinally of the bed-frame short shafts 20 are projected through the bed-frame, as best shown in Fig. 5, upon which shafts are provided bevel-gears 21 and 22, respectively, which mesh with corresponding bevel-gears 23 and 24 upon the shaft 25. Upon the shaft 25 is a driving-pulley 26, about which extends a belt 27, running to the pulley 28 upon the main driving-shaft 29, which latter shaft is supported within an upright frame hereinafter referred to. The driving-shaft 29 being constantly rotated, it is evident that the gears 21 and 22 should be normally out of engagement with the gears 23 and 24; but when it is intended to cause the matrix-table to travel either of the levers 30 or 31 is thrown so as to bring one pair of the gears 21 to 24 into engagement. When either pair of such gears is in engagement, its corresponding shaft 20 will be rotated, whereupon the chains 32 and 33 will be affected. Such chains 32 and 33 extend, respectively, to the matrix-frames A B, and it will be understood that the bed-frame is sufficiently long so that the table 5 may be carried, and with it such matrix-frames A B will be carried, to a position where either such matrix-frames will be brought into coincidence with the pressing means.

Carried by the bed-frame is an upright frame, which, as shown, is supported by means of the four upright columns or standards 35, which columns are braced by the inclined braces 36 and carry the transversely-extending connecting-beams 37 and cross-beams 38. Mounted upon the uprights 35 are bearings 39, in which is carried the main driving-shaft 29, upon which is the driving-pulley 40, actuated by the belt 41 from any suitable source of power. On the opposite end of the shaft 29 is carried the pulley 42, from which the crank-shaft pulley 43 is driven by a suitable belt 44, a belt-tightening means comprising the pivoted arm 45, link 46, lever 47, and loose pulley 48, coöperating with the belt 44 to

tighten such belt when desired to cause rotation of the pulley 43, and thereby actuate the crank-shaft 48^a, the lever 47 being pivotally connected with the bracket 49, as shown. Carried by the crank-shaft 48^a are hangers 50, 70 to which are pivotally connected the reciprocating rods 51, which rods terminate within the yokes 52, which yokes are connected rigidly with the plunger-head 53. Upon the plunger-rods 51 are collars or enlargements 54, and seated between the collars 54 and the horizontal upper end of the yokes 52 are compression-springs 55, adapted to receive the thrust of the plunger-rods and in turn communicate such pressure to the plunger-head 53, supplemental springs 56 being interposed between the lower end of the rods 51 and the bridges 57, connected with such plunger-heads, whereby a multiplicity of resilient cushioning means are provided between such 85 plunger-head and the source of power actuating the same. It will be understood that the plunger-head is perforated, such perforations being of a contour to correspond with the contour of the cores and semicores 8 and 9, so 90 that when the matrices A and B are filled and by means of the chains 33 carried to position beneath such plunger-head the plunger-rod may descend into the matrix which is in line therewith, and thereby press the material 95 within the matrix to the limit of compression possible with the power available. By interposing the cushioning-springs referred to between the plunger-rods and the plunger-heads it will be evident that a tamping effect may be 100 produced by reciprocating the plunger while a matrix is in position below the same, and the most perfect compression of the concrete mixture within the matrix is thereby produced.

While but one form of matrix is illustrated as an incident to the construction of the machine, it will be evident that matrices of various shapes may be used, either rectangular or of any other desired form, and cores of any desired conformation may be used in conjunction with such matrices upon substituting plunger-heads of the corresponding shape without in any manner changing any of the essential features of the machine, and the matrix illustrated in connection herewith is shown merely as a matter of illustration to exemplify the operation of the machine.

The operation of the machine is as follows, reference being had to Fig. 1: The matrix A is in position for filling and may be filled up to the level of the auxiliary frame, after which the proper lever is thrown, so as to actuate the proper shaft 20, thereby winding the proper chain upon its shaft and carrying the matrix A into position beneath the plunger-head. This will cause the table to travel in the direction indicated by the arrow in Fig. 1, carrying the matrix B to the right and the matrix A beneath the compression-plunger, 115 120 125 130

whereupon the plungers may be actuated, and while the material in the matrix A is being tamped the matrix B may be filled with concrete, after which the other lever is thrown, 5 so as to cause the table to travel in the opposite direction, whereupon the yoke 18 is released, the matrix-frame separated, and the pressed block removed from the matrix A upon the bottom plate 16, upon which it may 10 rest until the concrete has thoroughly set. In the meantime the matrix-frame may be re-assembled, a new bottom plate substituted for the plate 16, the cores and semicores again raised to position, after which the matrix may 15 be filled and the table caused to travel in the direction to bring it under the compression means for pressing the renewed supply of material.

While we have shown in the accompanying drawings the preferred form of our invention, it will be understood that we do not limit ourselves to the precise form shown, for many of the details may be changed in form or position without affecting the operativeness or 25 utility of our invention, and we therefore reserve the right to make all such modifications as are included within the scope of the following claims or of mechanical equivalents to the structures set forth.

30 Having described our invention, what we claim, and desire to secure by Letters Patent, is—

1. In a machine of the character described, a bed-frame, a slidable table mounted thereon, 35 a core-plate, cores thereon, screw-threaded adjusting-rods for said plate, a matrix-frame, a clamping-yoke adapted to secure said frame in closed position, a resilient plunger, and a plunger-head thereon provided with perforations therein of substantially the contour of said cores.

2. In a machine of the character described, a bed-frame, a slidable table mounted thereon, a core-plate, cores vertically adjustable with 45 relation to said table, a matrix-frame, a yoke secured to the table for locking said frame, shoulders in said frame, a perforated bottom plate resting thereupon, a plunger, and a perforated plunger-head co-operating therewith.

50 3. In a machine of the character described, a bed-frame, a slidable table mounted thereon, a core-plate, cores fixed thereupon and vertically adjustable with relation to said table, a matrix-frame having an internal seat, a perforated plate adapted to rest on said seat, a matrix-locking yoke secured to the table, and a cushioned plunger having a head provided with perforations registering with said cores.

4. In a machine of the character described, 55 a bed-frame, a slidable table on said frame, a

plurality of core-plates carried by said table, a plurality of adjusting-screws projected through the table into engagement with said plates, cores on the plates, means for sliding said table, a relatively fixed upright frame, 65 a crank-shaft mounted thereon, a plurality of plungers carried by said shaft, and a plunger-head having perforations adapted to register with said cores.

5. In a machine of the character described, 70 a bed-frame, an upright frame, a driving-shaft in said upright frame, a pulley thereon, a driven shaft in said bed-frame, bevel-gears thereon, cross-shafts, bevel-gears thereon, a 75 slidable table on the bed-frame, chains from opposite ends thereof to said cross-shafts, means for bringing said cross-shafts into operative engagement with said driven shaft, matrix-frames mounted on said table, and cores therein, in combination with a reciprocating plunger and a perforated plunger-head.

6. In a machine of the character described, 80 a bed-frame, a plurality of short shafts therein, bevel-gears on said shafts, a cross-shaft at an angle to said shafts, gears thereon, an upright frame, a driving-shaft mounted thereon, 85 a plunger-shaft, a pulley on said plunger-shaft, connections between said plunger-shaft, said driving-shaft and said cross-shaft, means for shifting said short shafts longitudinally 90 into engagement with said cross-shaft, a slid-able matrix-supporting table, matrices thereon, and a plunger-head actuated from said plunger-shaft.

7. In a machine of the character described, 95 a bed-frame, a slidable table thereon, core-plates carried by said table, cores connected with said plates, matrix-frames mounted on the table, clamping-yokes therefor, an upright frame, a crank-shaft mounted in said upright frame, a plurality of plunger-rods connected with said shaft, collars on said rods, a perforated plunger-head, perforated yokes on said plunger-head, and cushioning means between said head and said collars. 100

8. In a machine of the character described, 105 a matrix, cores supported therein, a perforated bottom plate, a perforated plunger-head, reciprocating plungers co-operating therewith, resilient cushions between said head and said plungers, means for actuating said plungers, and means for moving said matrix.

In witness whereof we have hereunto set our hands in the presence of two witnesses.

HENRY GUTTERIDGE.
JOHN HENRY McCONNELL.
